INVENTOR:

Edward P. Beach,

BY Braket Co. ATTY'S.

UNITED STATES PATENT OFFICE.

EDWARD P. BEACH, OF NEWARK, NEW JERSEY, ASSIGNOR TO UNGER BROTHERS, OF SAME PLACE.

DESIGN FOR A BRACELET.

SPECIFICATION forming part of Design No. 19,608, dated January 28, 1890.

Application filed December 10, 1889. Serial No. 333,285. Term of patent 8½ years.

To all whom it may concern:

Be it known that I, EDWARD P. BEACH, a citizen of the United States, residing at Newark, in the county of Essex and State of New Jersey, have invented and produced a new and original Design for Bracelets; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In said drawings, Figure 1 is an edge view of my design for bracelets, and Fig. 2 is a face or plan view of a section or portion thereof.

Similar letters of reference indicate like parts wherever they occur.

These two views are deemed sufficient to fully illustrate my design, the leading feature of which consists in the peculiar configuration presented by the surface of the manufacture or ornament. When viewed from the outside, the configuration is clearly represented in

Fig. 2, in which are shown two portions *c d*, 25 which are formed into curvilinear lines at the outer edges and which meet and interlock with one another at the center, and two other portions *a b*, formed into curvilinear lines and crossing one another through the center 30 and intertwined with said parts *c d*.

What I claim is—

The design for a bracelet herein shown and described, the surface of which shows two curvilinear lines at the outer edges interlocked 35 with each other at the center, and also interlaced through the center with two other portions formed into curvilinear lines crossing one another through the center and interlaced with the first portions, as set forth. 40

In testimony that I claim the foregoing I have hereunto set my hand this 4th day of December, 1889.

EDWARD P. BEACH.
